TANK SAFETY DEVICE

Delos W. Davisson and Ferdinand G. Welke, San Francisco, Calif., assignors to Shell Development Company, San Francisco, Calif., a corporation of Delaware

Application August 31, 1931, Serial No. 560,260

7 Claims. (Cl. 220—24)

This invention relates to containers for inflammable liquids and is more specifically concerned with the prevention of explosion of tanks used for transporting gasoline in bulk.

5 It is well known that gasoline and similar fluids are ever a menace of fire or explosion when in storage, and that they are even more dangerous when transported in bulk, as for instance, when the tanks containing gasoline are mounted upon 10 wheels and moved from place to place.

In order to minimize the danger of fire and explosion, most gasoline tanks are equipped with safety devices, such safety devices being a requirement by law in many jurisdictions. Various 15 types and forms of safety devices have been created and are in use. Some tanks are fitted with fusible plugs in the dome covers of each tank, so that in the event of the tank becoming heated, the plugs will melt, thus relieving the internal 20 pressure that would have built up inside the tank with the consequent danger of explosion. In practice these fusible plugs have not been found effective under all fire conditions, for instance, when there is a fire due to a leak in the bottom 25 of a tank. The plug being situated in the top of the tank is not near the seat of conflagration, so that the temperature of the tank may only be appreciably raised near the flames, and consequently the fusible plug will not be melted. The 30 heating of the gasoline inside the tank will cause a considerable pressure to be built up inside the tank. Often this pressure may be so great as to cause the tank to burst which may cause a great amount of damage.

35 Different types of vents have also been fitted to the tops of the tanks. Some of these vents have the disadvantage that if the tank is turned upon its side as may happen in an accident, the pressure of the liquid will cause the vent to jam in a closed position, thus making it useless for the purpose of relieving the internal pressure. Fire may then cause the tank to explode.

Some vents fitted to tanks are of small diameter so that sometimes when the tank is highly heated 40 as by fire the vents cannot cope with the rapid increase in pressure inside the tank due to vaporization of the contents and as a result the tank may burst.

Now we have found that by the use of a dome cover of our construction, the above disadvantages may be avoided.

The various features of our invention will be readily understood from the following detailed description throughout which reference is made 55 to the accompanying drawing.

Figure I is a plan view of the dome cover.

Figure II is a view in elevation of the dome cover through A—A of Figure I.

Figure III is a view in elevation showing the hinged end of the dome cover through C—C of 60 Figure I.

Figure IV is a view in elevation showing the fastener end of the dome cover through B—B of Figure I.

Referring to Figures I and II, (1) represents a 65 dome cover fitted to a seat (2) held in place by strongbacks (3) and clamping members (4). The seat is therefore rigidly attached to the tank (5) only part of which is shown. A gasket (6) is interposed between the seat and the tank to 70 make a gastight joint. Another gasket (7) is fitted to the dome cover for the same purpose.

The dome cover is at one end mounted upon a hinge pin (8) about which the cover can turn. The ends of the hinge pin are slidable traversely 75 in grooves (24) in raised sections (9) of the seat, as shown in Figure III.

The raised sections (9) are hollow on the inside, coiled springs (10) are interposed between the closed tops (11) and the hinge pin (8). The hinge 80 pin is prevented from falling out by pins (12).

The other end of the dome cover has a catch portion (13) which co-operates with a latch (14) attached to the seat.

The latch is mounted upon a hinge pin (15) 85 attached to the ends of which are link pieces (16) which are in turn fastened to a hinge pin (17).

The ends of this latter pin (17) are slidable traversely in raised sections of the seat (18) as at the anchored end of the dome. 90

By the use of the term "slidable traversely" we mean that the hinge pins are movable in directions perpendicular to their longitudinal axes.

The springs (19) at the latch end of the dome cover are more flexible than those at the hinged 95 end. The hinge pin (17) is prevented from falling out by a long pin (20). The long pin also acts as a stop for the latch when the dome cover is open.

In the middle of the dome cover is a one way air inlet valve (21) having air inlet holes (22) and a 100 ring valve piece (23).

For the filling operation the dome cover is used in the ordinary way by releasing the latch (14) and turning the cover back upon its hinge.

In the closed position the dome cover is normally airtight upon the flange (2) due to the pressure of the springs upon the hinge pins (8) and (17).

The springs are of such strength that an internal pressure of about three pounds per square 110

inch will cause the cover to further compress the springs, so that the hinge pins will move upward in the grooves (24) allowing the cover to raise from its seat and release the pressure inside the 5 tank.

It will be readily understood that by changing the springs we may cause the cover to open at any desired pressure below the bursting point of the tank to which the cover is fitted.

- 10 A slight internal pressure may exist in a tank fitted with our dome cover. An internal pressure will exist in a tank so fitted when the gasoline in the tank is raised to a higher temperature than the temperature of the gasoline when it was loaded. Such a condition will exist when the tank is used in a hot climate. The existence of this internal pressure reduces loss of light fractions of the gasoline by evaporation, as well as materially aiding in the discharge of gasoline from the tank.
- 15 20 Among the other advantages resulting from the use of our dome cover may be mentioned the following:

As the dome cover is fitted with an air inlet valve a vacuum cannot exist in the tank and thus retard the emptying of the tank. The dome cover being held in place by springs prevents a high pressure being built up within the tank so that the danger of explosion is avoided. Even if the tank is turned upon its side the dome cover will 25 still prevent explosion of the tank, as the cover will raise to release excess internal pressure, but will close when this pressure has been released, thus reducing the amount of liquid lost.

30 A further advantage of our dome cover when fitted to tanks mounted upon motor truck chassis or upon motor truck trailers is that when going up hill or over an uneven road with a full tank of gasoline, spilling of the gasoline cannot result owing to the normally airtight construction.

35 40 While in the above specification we have described our dome cover as applied to tanks used for the transportation of gasoline it should be understood that we may apply our dome cover to gasoline storage tanks or to tanks used for the 45 storage or transportation of other inflammable liquids.

We claim as our invention:

1. A safety dome cover assembly comprising a dome cover, a seat below said dome cover, a hinge pin connecting the dome cover to one end of said seat, a latch attached to the other end of the seat, a hinge pin connecting said latch to the seat and springs above the hinge pins, said hinge pins being slidably mounted in the seat.

50 55 2. A tank truck dome cover assembly comprising: a dome cover, a seat below said dome cover,

a hinge pin slidably connecting the dome cover to one end of said seat, springs under compression in the seat above said hinge pin, a second hinge pin slidably connecting a latch to the opposite end of said seat, springs under compression in the seat above said second hinge pin, and means whereby the latch cooperates with the dome cover to hold said dome cover in yieldable contact with said seat.

80 85 90 3. A tank truck dome cover assembly comprising a dome cover, a seat below said dome cover, a hinge pin slidably connecting the dome cover to one end of said seat, springs under compression above said hinge pin in hollow sections of said seat, a second hinge pin, slidably connecting a latch to the opposite end of said seat springs under compression above said second hinge pin in hollow sections of said seat and means whereby the latch cooperates with the dome cover to hold said dome cover in yieldable contact with said seat, substantially as described.

95 4. A safety dome cover assembly comprising a dome cover, a seat below said dome cover, a latch, a link attached to said latch, a hinge pin connecting said link to said seat, said hinge pin being 100 slidable in said seat at right angles to the longitudinal axis of said hinge pin, and springs under compression above said hinge pin whereby said dome cover is held in yieldable contact with said seat.

105 5. A safety dome cover assembly comprising a dome cover, a seat below said dome cover, a latch, links attached to said latch, a hinge pin connecting said links to said seat, said hinge pin being 110 slidable in said seat at right angles to the longitudinal axis of said hinge pin and springs under compression above said hinge pin whereby said dome cover is held in yieldable contact with said seat.

115 6. A safety dome cover assembly comprising a dome cover, a seat below said dome cover, a hinge pin connecting one end of said dome cover to said seat, said hinge pin being 120 slidable in said seat at right angles to the longitudinal axis of said hinge pin and springs above said hinge pin in hollow sections of said seat.

125 7. A dome cover assembly comprising a dome, a seat below said dome cover, a hinge pin connecting the seat to the dome cover, said hinge pin being 130 slidable in said seat at right angles to the longitudinal axis of said hinge pin, springs in said seat contacting said hinge pin whereby said dome cover is held in yieldable contact with said seat.
